(57) **CLAIM**

The ornamental design for a push broom bracket, as shown and described.

DESCRIPTION

FIG. 1 is a perspective view of the push broom bracket according to our design showing how this bracket is attached to a push broom and a push broom handle. The push broom and push broom handle form no part of this design.

FIG. 2 is an enlarged front elevational view of the push broom bracket of FIG. 1.

FIG. 3 is an enlarged side elevational view of the push broom bracket of FIG. 1.

FIG. 4 is an enlarged rear elevational view of the push broom bracket of FIG. 1.

FIG. 5 is an enlarged top plan view of the push broom bracket of FIG. 2; and,

FIG. 6 is an enlarged bottom plan view of the push broom bracket of FIG. 2.
